UNITED STATES PATENT OFFICE.

ROBERT M. HINMAN, OF AKRON, OHIO, ASSIGNOR OF ONE-HALF TO FRANK NOLTE, OF AKRON, OHIO.

PROCESS FOR MAKING CORES FOR MANUFACTURING TIRE-SHOES.

1,037,250.

Specification of Letters Patent.

Patented Sept. 3, 1912.

Original application filed December 1, 1909, Serial No. 530,876. Divided and this application filed October 30, 1911. Serial No. 657,520.

To all whom it may concern:

Be it known that I, ROBERT M. HINMAN, a citizen of the United States, residing at Akron, in the county of Summit and State 5 of Ohio, have invented new and useful Improvements in Processes for Making Cores for Manufacturing Tire-Shoes, of which the following is a specification.

This invention relates to improvements in processes or methods for manufacturing cores or mandrels such as are commonly used in the making of outer tire-shoes of double-tube pneumatic tires having inextensible or uninextensible bands or selvages, 10 and is a division of an application filed by me Dec. 1, 1909, Serial No. 530,876. Heretofore cores of this type have been cast annularly, after which they are placed in a suitable machine and the outer surface 15 turned to the shape which is desired to impart to the interior of the finished tire-shoe and on which the tire-shoe is to be built. The annular core-body is then cut into a plurality of segments by hack-saws or other 20 suitable means so as to divide the cores into suitable portions to permit the removal of one segment after another from the inner open portion of the tire-shoe after vulcanization. These cuts, however, which sever 25 the annular body of the cores into a plurality of segment-shaped members remove so much of the material of the core that when the segment-shaped members are again assembled the resulting product does 30 not form a true circle and hence, it becomes imperative in such cases to secure filler-blocks or plates on the ends of one or both of the abutting faces of the segment-shaped members to compensate for the loss incident 35 to the cuts made in severing the cores into segments. Further it is necessary that these 40 filler-blocks or plates be secured rigidly to the ends of the segment-shaped members and as this requires drilling and tapping 45 holes or providing dowel-pins for riveting the same in position the loss of time and labor involved is a considerable item.

This invention contemplates first casting the ring-core as an integral body, previous 50 to which there is interposed in the mold-cavity and serving to divide the same into a number of separate cavities, a plurality of thin plates of suitable heat-resisting material each having an opening therein by

which the molten metal passes from one 55 segment-shaped compartment of the mold into another to unite the entire core-body into an integral member, the inserted plates being usually united with the core-body by the casting operation, but being cold they 60 do not fuse therewith. After the core has been cast it is placed in a suitable machine and the outside finished to impart to the exterior surface thereof the desired conformation which it is sought to impart to the interior of the tire-shoes to be formed thereon after which the core-body is broken into 65 segment-shaped members at the points where the interposed plates are positioned. In practice, the interposed plates will customarily attach to one or the other of the abutting ends of the segment-shaped members but, if for any reason they do not attach themselves to the segment-shaped 70 members, they may be afterward united 75 therewith by suitable hold-fast devices.

From the foregoing it will be seen that the interposition of the plates in the molds and having apertures therein to permit the molten metal to pass through the same and 80 to unite the metal of coadjacent segment-shaped members accomplishes the function of uniting the entire core into a unitary mass during the finishing of the exterior thereof and also provides frangible joints 85 between contiguous segment-shaped members of the core, which will permit the small connecting portions forming the frangible joints to be easily broken to separate the core into a plurality of independent 90 segment-shaped members adapted to be afterward united or abutted end to end to form an annular core-body and to be held in position through the medium of auxiliary means, the resulting product being an annularly-formed core-body comprising a 95 plurality of segment-shaped members capable of being detached when necessary and reassembled for reuse.

With the foregoing and other objects in view, the invention consists in the novel method for constructing a core, said method constituting the invention to be hereinafter more specifically described in connection with the accompanying drawings, reference 100 to which is therein made.

In the drawings in which similar reference numerals indicate like parts in the different

- figures; Figure 1, is a plan view of a core constructed by utilizing my improved method; Fig. 2, is a sectional view of the core shown in Fig. 1 on line X thereof; 5 Fig. 3, is an end elevation of one of the core members detached showing the interposed filler-plate secured thereto; and, Fig. 4, is a longitudinal central sectional view enlarged of the core shown in Fig. 1.
- 10 In constructing a mold for ring-cores in accordance with this invention an ordinary mold is employed, which is preferably provided with a cavity of suitable conformation to form an annular core 1 having a 15 body-portion of approximately the shape which it is desired to impart to the interior of the finished tire-shoe, and further provided with an inwardly-extending flange 2 having on opposite faces thereof annular 20 grooves 3, with the inner and outer walls of said groove 3 inclined as shown in the drawings. Before the casting operation there is interposed in the cavity of the mold a plurality of plates 4 extending across the 25 cavity and arranged obliquely to the radii thereof and preferably arranged as shown in Fig. 1. These plates are provided with apertures 5 through which the molten metal which forms the core may pass from one 30 segment-shaped cavity of the mold to an adjoining cavity to thereby unite all portions of the core into an integral mass when the metal cools. These plates are generally made larger than the cavity in the mold in 35 either the cope or drag thereby securely anchoring the plates in the same to provide against their being unintentionally displaced by the molten metal during the casting operation. In casting these ring-cores or 40 mandrels they are usually formed with cavities 6 therein which is accomplished by the employment of ordinary sand-cores, the sand-cores in each segment-shaped cavity or mold stopping short of the ends of the 45 cavities to provide solid walls of metal at the ends of the segment-shaped members in the finished product. After the ring-core has been cast, the device is placed in a suitable machine such as a boring mill and the 50 exterior thereof turned to the exact shape which it is desired to impart to the interior of the tire-shoe to be built thereon.
- Previous to the turning or finishing of the exterior of the core the surplus portions of 55 the plate 4 which extend beyond the outline of the core-body are cut or broken away, usually by hand. During this latter operation the abutting ends of the segment-shaped portion being firmly united by the metal 60 which extends through the apertures 5 and the interposed plates 4 prevent them from being displaced. After the exterior of the core has been turned to impart the desired cross section configuration thereto, the various segments are broken apart, in doing 65

which it is only necessary to fracture the neck portion of each segment-shaped member which extends through the apertures 5 in the plates 4 which are positioned on the ends of the members, after which the plates 4, if they become loosened from the segment-shaped members, may be secured to one of the ends of each of the segment-shaped portions through the medium of hold-fast devices such as screws 7.

75 It will be noted that the apertures 5, as shown in Fig. 4 are frusto-conically-formed so that the metal extending in these apertures is smaller in diameter at one side of the plate than at the other and the segment-shaped members are customarily separated or broken apart on the line where the thickness of the metal extending from the aperture is smallest and weakest, thus constituting a frangible joint between adjacent 80 and contiguous segment-shaped portions of the preformed annular core-body.

85 In use after the segment-shaped members have been broken apart to make them independent of each other they are reassembled 90 for use and held in position through the medium of two rings 8 clamped over the sides of the flanges of contiguous segments for maintaining them in annular formation. These rings are preferably clamped together 95 through the medium of bolts 9 which extend through the flanges of the segment-shaped members and serve to maintain them and the rings in proper relation with respect to each other thereby providing easy removable 100 means for permitting the collapsing of the core by the successive withdrawal of the various segments thereof through the inner opening in the body of the tire-shoe which is made thereon.

105 I claim:

1. A method of manufacturing cores for forming the outer shoes of double-tube pneumatic tires, consisting in inserting in an annular mold-cavity a dividing medium 110 provided with means for permitting a small portion of the metal in one portion of the cavity to unite with the metal in a coadjacent cavity, thereby providing a frangible joint between coadjacent segments of a finished core, causing said dividing medium to adhere to the end of one of said segments, and subsequently breaking said sections apart to provide a collapsible core capable of being reassembled into an annular body. 115

120 2. That improvement in methods for manufacturing cores for forming the outer shoes of double-tube pneumatic tires, which consists in incorporating in an annular mold-cavity a plurality of apertured dividing mediums each provided with means for permitting a small connecting portion of the metal in coadjacent portions of the mold-cavity to unite through said dividing medium thereby providing a frangible joint 125 130

between said coadjacent portions of the finished core, securing said dividing mediums to the ends of said core portions and subsequently breaking said sections apart at said 5 frangible joints and along one face of each of said dividing mediums to permit the re-assembling of said core-forming portions into an annular body.

In testimony whereof I have hereunto set my hand in presence of two suscribing wit- 10 nesses.

ROBERT M. HINMAN.
